UNITED STATES PATENT OFFICE.

HENRY G. KURTZHALS, OF SOMERSET, PENNSYLVANIA.

AUTOMATIC BLOCK SYSTEM.

1,096,729.

Specification of Letters Patent. Patented May 12, 1914.

Application filed October 22, 1912. Serial No. 727,179.

To all whom it may concern:

Be it known that I, HENRY G. KURTZHALS, a citizen of the United States, residing at Somerset, in the county of Somerset and State of Pennsylvania, have invented new and useful Improvements in Automatic Block Systems, of which the following is a specification.

This invention relates to a block signal system for railroads, the primary object thereof being to provide electrical apparatus at the intersection of the successive blocks and adapted to be controlled by the visual signal devices at these points, in order that, whenever the signal arm is raised into danger position, at the beginning of any block, the apparatus at this point will coöperate with train carried signal devices upon a train which may be approaching the block to actuate both audible and visible signal devices within the engine cab. In this manner, the engineer is notified positively of the presence of a train in an advance block, should such a condition exist, upon passing the signal mast disposed at the side of the track to warn him of this fact, thus preventing danger of collision when the engineer fails to see the track signal, due to adverse weather conditions, or like causes.

A further object of the invention is to provide a device of this character which is very simple in construction, and which will be efficient and positive in action.

With these and other objects in view, the invention consists of certain novel features of construction, combination and arrangement of parts, as will be hereinafter described and claimed.

In the accompanying drawings:—Figure 1 is a fragmentary side elevation of a railroad track and a locomotive thereon, showing the cab signal apparatus in use; Fig. 2 is a fragmentary front elevation of the track device, showing the circuit closer in closed position; Fig. 3 is a diagrammatic view, showing a train located in one block and a second train approaching from the rear in the next succeeding block with the signal devices in their corresponding position.

Referring to the drawings, and in particular to Fig. 3, the reference characters A,

B and C designate the insulated track sections or blocks of a railroad, each track section including the rails 1 and 2 whose ends are insulated, as at 3 and 4, from the corresponding rails of the adjacent sections. It is to be understood in the first place that signal masts 5 are provided at the ends of each block and which have the vertically swinging signal arms 6, which latter are adapted to be operated by suitable mechanical or electrical train actuated means to set the said arm 6 of each device in its uppermost danger position as a train passes the mast and advances into the next succeeding block or track section.

Each signal mast 5 has mounted thereon a suitable block or receptacle 7, in which is provided a circuit closing device 8. This device includes a pair of wedge-shaped contact members 9 and 10 having beveled engaging faces 11 and 12, respectively. The upper end of the lowermost contact member 10 is connected by means of a vertically extending flexible rod 13 with the signal arm 6 adjacent its pivot 14, and the lower end of the member 10 is connected by means of a flexible conductor 15 with a binding post 16. A conductor 17 extends from the binding post 16 to one terminal of a track battery 18, the other terminal of this battery being connected by a suitable conductor 19 with the track rail 2 of the section disposed in advance of the signal mast. This construction is shown most clearly in Figs. 1 and 2 of the drawings. The contact member 10 is thus movably mounted within the box 7, due to its attachment to the lower end of the rod 13. The contact member 9, however, is fixed to the upper end of the box, and its lower end or apex is connected by means of a conductor 20 with a binding post 21. From thence a conductor 22 extends to its point of attachment with an auxiliary rail 23 which rail is disposed in advance of the track section. This auxiliary contact rail may be disposed between the main track rails or at either side thereof, it being necessary to have the upper contact surface 24 thereof disposed a short distance above the level of the tread surface of the main rails, in order to permit the train-carried contact shoe to be disposed high enough to prevent its be-

coming engaged with the trackway at crossings, bridges or the like.

Each locomotive is provided with a vertically movable contact device 25, which is normally maintained in its lowermost position by means of an extensile spring 26 and which is provided on its lower end with an arcuate shoe 27. This shoe is adapted to engage the tread surface 24 of each auxiliary rail 23 as the train passes along, it being maintained in firm contact therewith during the passage of the train by the action of the spring 26. The contact device 25 is connected by means of a conductor 28 with a lamp 29 and an audible signal such as a bell 30, which is connected preferably in series with the lamp, and a second conductor 31 connects these devices with one of the wheel axes 32.

20 In order to understand the operation of the device, reference should be had to Fig. 3 of the drawing, wherein a locomotive D is preceding a locomotive E along the track, the former being disposed in the block B whereas the latter is located in the block C. As there is no train in the block A, the signal arm located at the juncture of the blocks A and B will be in its lowermost, safety position, thus rendering the track device at this point inoperative, due to the fact that the circuit closing device is in open position. The signal arm at the juncture of the blocks B and C, however, is in its elevated danger position, thus causing 35 the circuit closing device in the track apparatus at this point to be in its closed position, one side of the track circuit being thus closed. As the locomotive E approaches the end of the block C, the contact shoe 27 carried thereby will come in contact with the auxiliary rail at this point, thus completing the local circuit through the train carried audible and visual signal devices, thus insuring the proper stopping of the train by 45 giving the engineer an unmistakable warning, even though he fails to see the signal arm at this point.

Having thus described my invention, what I claim is:

50 1. The combination with a signal mast having a vertically swinging semaphore arm, and a normally open train signal circuit, of a circuit closer for one side of said circuit comprising a casing carried by the said mast and affording a vertical guide, a fixed contact member mounted within said casing in connection with one terminal of the said circuit and having a beveled under face, a movable contact member connected with the other terminal of the said circuit and mounted for sliding movement within the casing and having a beveled upper face for engagement with the beveled face of the

fixed member, and means connecting the movable contact member with the semaphore 65 arm for supporting the former in engagement with the fixed contact when the said arm is in its uppermost danger position.

2. The combination with a signal mast having a vertically swinging semaphore 70 arm, and a normally open train signal circuit, of a circuit closer for one side of said circuit comprising a casing carried by the said mast and affording a vertical guide, a fixed contact member mounted within said 75 casing in connection with one terminal of the said circuit and having a beveled under face, a movable contact member connected with the other terminal of the said circuit and mounted for sliding movement within 80 the casing and having a beveled upper face for engagement with the beveled face of the fixed member, means connecting the movable contact member with the semaphore arm for supporting the former in engagement with 85 the fixed contact when the said arm is in its uppermost danger position, and yieldable means for maintaining the movable contact member in its lowermost, inoperative position.

90 3. The combination with a signal mast having a vertically swinging semaphore arm, and a normally open train signal circuit, of a circuit closer for one side of said circuit comprising a casing carried by the 95 said mast and affording a vertical guide, a fixed contact member mounted within said casing in connection with one terminal of the said circuit and having a beveled under face, a movable contact member connected 100 with the other terminal of the said circuit and mounted for sliding movement within the casing and having a beveled upper face for engagement with the beveled face of the fixed member, and a flexible member connecting the semaphore arm with the movable contact member for supporting the latter in engagement with the fixed contact member when the said arm is in its uppermost 105 danger position.

110 4. The combination with a signal mast having a vertically swinging semaphore arm, and a normally open train signal circuit, of a circuit closer for one side of said circuit comprising a casing carried by the 115 said mast and affording a vertical guide, a fixed contact member mounted within said casing in connection with one terminal of the said circuit and having a beveled under face, a movable contact member connected 120 with the other terminal of the said circuit and mounted for sliding movement within the casing and having a beveled upper face for engagement with the beveled face of the fixed member, a flexible member connecting 125 the semaphore arm with the movable contact

member for supporting the latter in engagement with the fixed contact member when the said arm is in its uppermost danger position, and yieldable means provided in the casing in connection with the movable contact member for normally maintaining the same in its lowermost inoperative position.

In testimony whereof I affix my signature in presence of two witnesses.

HENRY G. KURTZHALS.
